UNITED STATES PATENT OFFICE.

ABRAHAM COUWENHOVEN, OF BADEN, SWITZERLAND, ASSIGNOR TO A. G. BROWN BOVERI & CIE., OF BADEN, SWITZERLAND, A JOINT-STOCK COMPANY OF SWITZERLAND.

SAFETY DEVICE FOR TRACTION OPERATION.

Application filed March 4, 1926, Serial No. 92,325, and in Italy May 27, 1925.

This invention relates to electrical railways, particularly to that class in which different portions of the system are supplied at different voltage.

5 The general object of the invention is the provision of automatically operating means for insuring the proper adjustment of switch mechanism on the vehicle incident to its passing from the zone of one voltage to that of another.

10 Other objects will be pointed out or indicated hereinafter or will be obvious to one skilled in the art upon an understanding of the invention.

15 In the drawing forming a part of this specification I show one arrangement, but this is presented for purpose of illustration only and is not to be interpreted as limiting the claims in any fashion short of the true 20 and most comprehensive scope of the invention in the art.

In the drawing, the figure is a diagrammatic illustration of one arrangement of apparatus embodying the invention.

25 When electric railways or tramways are worked at more than one voltage, as for example when the country sections are worked at double the voltage of the urban sections, precautions must be taken to prevent the connections as set for low-voltage operation remaining unaltered when the vehicle passes into a high-voltage section of the line, even when the driver forgets to change the connections or is prevented from doing so.

30 According to the invention the main switch is open automatically in such circumstances when the vehicle arrives at the transition point. This is done by arranging a lever on the car which strikes against a ramp on the track and opens the main switch in the event 40 of the car passing on to the high voltage section with the connections set for low voltage operation. The main switch can only be reclosed after the driver has made the required 45 change in the connections.

The drawing shows diagrammatically an example of the application of the invention to a car on which the main switch is operated by compressed air. In the drawing *c* is the 50 drum of the controller for which *d* represents the low voltage and *e* the high voltage positions. The shaft of the controller is extended and divided into two portions *a* and *b* by a

clutch *h* which is operative in one direction only. Two air cocks *f* and *g* are arranged on the two sections of the shaft as shown.

55 The drawing shows the control gear in the position for low voltage operation. Compressed air enters at *m*, passes through the passage *n* of the cock *f*, the connecting pipe *o* and the passage in the cock *g* to the cylinder *p* where the pressure it exerts against the spring controlled piston is sufficient to keep the main switch *q* closed. The air pipe *r* which communicates with the atmosphere 60 at *t* through the passage *s* in cock *f* is isolated by the cock *g*.

65 The automatic tripping of the main switch is effected by providing a ramp or guide rail *u* attached to the track at the transition point. A striking lever *v* is suitably arranged on the car and connected to the free portion *b* of the control shaft by a chain.

70 In normal circumstances the driver, on reaching the transition point, turns the handle *k* and with it the controller drum *c* from position *d* to position *e*. At the same time the air cock *f*, and, through the medium of the clutch *h*, the cock *g* also, are both turned through 90°, thus putting the inlet 75 pipe *m* into communication with the cylinder *p* by way of the passage *s*, connecting pipe *r*, and the passage in cock *g*.

75 Should the driver have left the drum *c* in the low-voltage position *d*, however, the lever *v* strikes against the rail *u* in the direction of the arrow as the car advances and takes up the position indicated by the dotted lines. This rotates the portion of the shaft *b* carrying the air cock *g*, the shaft portion *a* remaining undisturbed. The cylinder *p* is thus opened to atmosphere by way of the cock *g*, connecting pipe *r* and passage *s* in cock *f*, the pressure is removed and the main switch *q* opens bringing the car to a standstill. 80 85 90 95

To close the switch *q*, compressed air must be supplied to the cylinder *p* and this can only be done by the driver moving his control lever from position *d* to position *e*. When passing from high to low voltage operation the uni-directional action of the clutch *h* causes the shaft portion *b* to be left behind when the handle *k* is turned back from position *e* to position *d*. Consequently it must be returned by the driver with the aid of a special handle *i*, which at the same time 100 105

returns the striking lever *v* to the full line position corresponding to low-voltage operation.

What I claim is:—

- 5 1. A protective device for traction motors operating on multi-voltage systems, comprising: a change-over switch on the vehicle, a divided shaft for controlling said switch, a hand operable means for adjusting said shaft, 10 a throwing device at the junction of high and low voltage sections of the system, and means on the vehicle operable thereby for actuating one section of said shaft.
- 15 2. The combination with an electrically propelled vehicle adapted to operate on sections having current of different character, of a change-over switch on said vehicle to establish circuits in accordance with the character of the current to be operated with, a 20 main switch controlling the current supply to said vehicle, a throwing device at the junction of the sections operating with currents of different character, means on the vehicle operable by said throwing device for opening 25 said main switch in case said change-over switch is not in the position corresponding to the character of the current in the section toward which said vehicle is moving.
- 30 3. In a trolley vehicle system, a trolley section of low voltage, and an adjoining trolley section of relatively high voltage, an electrically propelled vehicle supplied from said trolley sections, a change-over switch on said vehicle for operating the same with connections 35 suitable for low voltage operation or with connection suitable for high voltage operation, a main line switch on said vehicle, a throwing device at the junction of the high voltage and low voltage sections and means 40 on said vehicle adapted to be actuated by said throwing device to open said main switch when passing from one section to the other.
- 45 4. In a trolley vehicle system, a trolley section of low voltage, and an adjoining trolley section of relatively high voltage, an electrically propelled vehicle supplied from said trolley sections, a change-over switch on said vehicle for operating the same with connections 50 suitable for low voltage operation or with connections suitable for high voltage operation, a main line switch on said vehicle, a throwing device at the junction of the high voltage and low voltage sections, means on 55 said vehicle adapted to be actuated by said throwing device to open said main switch when passing from one section to the other, and means for preventing re-closure of said main switch until said change-over switch is in the position corresponding to the voltage 60 of the section to be operated upon.
- 65 5. In a trolley vehicle system, a trolley line comprising a high voltage section and a low voltage section, an electrically propelled vehicle adapted to be supplied by said trolley line, a main line switch on said vehicle, a

change-over switch for establishing low voltage and high voltage operating connections, a throwing device at the junction of the low and high voltage sections, and interlocking means between said main switch and said change-over switch so arranged as to cause said throwing means to open said main switch when passing from the low voltage section to the high voltage section when the change-over switch is in the low voltage position and causing said main switch to remain closed when said change-over switch is in the high voltage position. 70

6. In a trolley vehicle system, a trolley line comprising a high voltage section and a low voltage section, an electrically propelled vehicle adapted to be supplied by said trolley line, a main line switch on said vehicle, a change-over switch for establishing low voltage and high voltage operating connections, a throwing device at the junction of the low and high voltage sections, interlocking means between said main switch and said change-over switch so arranged as to cause said throwing means to open said main switch when passing from the low voltage section to the high voltage section when the change-over switch is in the low voltage position and causing said main switch to remain closed when said change-over switch is in the high voltage position, and means for preventing re-closure of said main switch until said change-over switch is brought to the high voltage position. 80

7. A protective device for traction motors operating on a system having high and low voltage sections, comprising, in combination, a main switch on the vehicle, a throw-over switch on the vehicle, a control device for the main switch, a throwing device at the junction of such sections for cooperation with the control device to cause opening of the main switch, and means operable in conjunction with the throw-over switch for causing closing of the main switch. 90

8. A protective device for traction motors operating on a system having high and low voltage sections, comprising, in combination, a main switch on the vehicle, a throw-over switch on the vehicle, manually-controlled means for operating the throw-over switch, a control device for the main switch, a throwing device at the junction of such sections for cooperation with the control device to cause opening of the main switch, and means operable in conjunction with the throw-over switch for causing closing of the main switch. 105

9. A protective device for traction motors operating on a system having high and low voltage sections, comprising, in combination, a main switch on the vehicle, a throw-over switch on the vehicle, a control device for the main switch, a manually-operable setting device for the throw-over switch, a throwing device at the junction of such sections for ac- 115

125

130

tuating the control device, and means under control of the setting device for actuating the control device.

10. In apparatus for controlling an electric vehicle disposed for operation along co-extensive high and low voltage supply lines, a supply switch carried by such vehicle, means carried by such vehicle and having a first and a second position and being operable when in said first position to provide for low voltage operation of said vehicle and being operable when in said second position to provide for high voltage operation of the

same, relatively fixed means disposed at the junction of such lines, and means carried by such vehicle and disposed for coaction with said relatively fixed means and being operable upon such coaction and concurrent disposition of said first-named means in said first position thereof to effect opening operation of said supply switch. ¹⁵ ²⁰

In testimony whereof, I have hereunto subscribed my name at Zurich, Switzerland, on the 10th day of February, A. D. 1926.

ABRAHAM COUWENHOVEN.

CERTIFICATE OF CORRECTION.

Patent No. 1,687,084.

Granted October 9, 1928, to

ABRAHAM COUWENHOVEN.

It is hereby certified that error appears in the above numbered patent requiring correction as follows: Page 1, in the heading to the printed specification, line 6, date of filing application in Italy, for "May 27, 1925" read "March 27, 1925"; and that the said Letters Patent should be read with this correction therein that the same may conform to the record of the case in the Patent Office.

Signed and sealed this 5th day of February, A. D. 1929.

(Seal)

M. J. Moore,
Acting Commissioner of Patents.
